CIGARETTE PACKAGE CONTAINER

Leo Willens, New York, and Arthur W. Meldrum,
Brooklyn, N. Y.

Application April 5, 1935, Serial No. 14,860

3 Claims. (Cl. 206—48)

The invention relates to containers of the type adapted to hold a package of cigarettes and containing a plurality of matches for convenient use with the cigarettes. This invention has for one 5 of its main objects to provide a container of improved construction which will be more convenient as well as safer and more sanitary than any of the containers, of this type, shown in the prior art.

10 Another object is to provide a container of neat, but simple, construction which can be manufactured and sold at a comparatively low price and which provides a maximum area which may be utilized for advertising purposes.

15 These and various other objects and advantages will be readily understood from the following description and from the accompanying drawing of a preferred embodiment of the invention, in which, however, modifications may be made without departing from the scope of the appended claims. In the drawing

Fig. 1 is a perspective view of the container shown with a package of cigarettes inserted.

20 Fig. 2 is another perspective view shown with the container empty and with one of the match covers opened.

Fig. 3 is a similar view shown with both the match covers opened, and

30 Fig. 4 is a plan view showing the blank from which the container is formed.

Referring now to all the views, simultaneously, the container is preferably made from a blank as illustrated in Fig. 4 and consists of a front part 10, a rear part 11, two side members 12 and 13, an end member 14 having a tongue 15, and two match covers 16 and 17. The blank is folded as indicated by the broken lines and the flap 18 is pasted or otherwise secured to the front part 10. The container is made of a size suitable to hold a package of cigarettes 19.

40 A plurality of matches 20, preferably of the paper type is secured on the rear of the container, as is also a piece of the ordinary striking material 21. The cover 16 is adapted to be folded over the matches, but a part of this cover is cut away, as shown at 22, so that the striking material 21 is exposed, even when this cover is closed. The cover 17 is adapted to be folded over the cover 16 and is provided with a tongue 23 which fits in a slit 24 cut in the cover 16. When this tongue is inserted in the slit, as shown in Fig. 1, the two covers are effectively locked over the matches.

45 From this description it will be seen that there is no danger of the covers opening up when the

5 container is inserted in the pocket of its user. It will also be noted that the cover 16 may be folded over the matches when a match is being lit, thus avoiding any danger of the remaining matches being ignited. The striking material, which always becomes quite soiled after matches have been struck on it, is covered by the cover 17 when the container is laid away or carried in a pocket or purse. And, furthermore, the cover 17 can be used as a shield when a match is lit in 10 a draft or in windy weather.

Having described the invention and its advantages, what we claim as new and wish to protect by Letters Patent is:

15 1. A container of the class described comprising a blank cut and folded to form a compartment for a package of cigarettes, a plurality of matches secured on the outside of the container, a piece of match-striking material secured at the lower end of said matches, a cover for covering said matches, an opening formed in said cover for exposing said match-striking material when the cover is closed, and a second cover for overlapping engagement with said first-mentioned cover and for closing the opening therein. 20

25 2. A container of the class described comprising a blank cut and folded to form a compartment for a package of cigarettes, a plurality of matches secured on the outside of the container, a piece of match-striking material secured at the lower end of said matches, a cover for covering said matches, an opening formed in said cover for exposing said match-striking material when the cover is closed, a second cover for overlapping engagement with said first-mentioned cover and for closing the opening therein, and means for locking the outer cover to the inner cover. 30

35 3. A container of the class described comprising a blank cut and folded to form a compartment for a package of cigarettes, a plurality of matches secured on the outside of the container, a piece of match-striking material secured at the lower end of said matches, a cover for covering said matches, an opening formed in said cover for exposing said match-striking material when the cover is closed, a second cover for overlapping engagement with said first-mentioned cover and for closing the opening therein, means for locking the outer cover to the inner cover, and the 40

45 outer cover acting as a shield when a match is being lit. 50
